ENGINE STARTER GEARING

Thomas B. Martin, Dayton, Ohio, assignor to
 Bendix Aviation Corporation, South Bend, Ind.,
 a corporation of Delaware

Application October 18, 1940, Serial No. 361,755

16 Claims. (Cl. 74—7)

The present invention relates to engine starter gearing and more particularly to a drive for automatically connecting and disconnecting a starting motor with a member of the engine to be started.

It is an object of the present invention to provide a novel engine starter drive which is effective in operation, economical in construction and small in size as compared to standard drives of like capacity.

It is another object to provide such a device embodying a compressible cushioning element with a threaded connection for applying pressure thereto, and a separate threaded connection for traversing a pinion into and out of engagement with a member of the engine to be started.

Further objects and advantages will be apparent from the following description taken in connection with the accompanying drawings in which:

Fig. 1 is a side elevation partly in section of a starter drive embodying a preferred form of the invention;

Fig. 2 is a similar view of a drive of the same type as Fig. 1, adapted for outboard installation;

Fig. 3 is a section taken substantially on the line 3—3 of Fig. 2;

Fig. 4 is a side elevation partly in section of another embodiment of the invention;

Fig. 5 is a view similar to Fig. 4 showing the parts in driving position;

Fig. 6 is a side elevation partly in section of another form of the invention;

Fig. 7 is a side view partly in section of a further embodiment of the invention;

Fig. 8 is an end view from the right of the structure shown in Fig. 7;

Fig. 9 is a view similar to Fig. 7 showing the parts in driving position;

Fig. 10 is a section taken substantially on the line 10—10 of Fig. 7; and

Fig. 11 is a detail in perspective of the pinion and threaded operating members therefor, as illustrated in Figs. 7 to 10, shown in disassembled relation and partly broken away for the sake of clarity.

In Fig. 1 of the drawings there is illustrated a power shaft which may be the extended armature shaft of a starting motor, not illustrated. Shaft 1 is provided with a smooth reduced portion 2 forming a shoulder 3. A plurality of spline grooves 4 are formed in the power shaft beyond the smooth portion 2, and a further reduced smooth portion 5 is provided beyond the splined portion, the surface of the portion 5 being flush

with the bottoms of the spline grooves, leaving shoulders 6 at the end of the splined portion.

A pinion 7 is slidably journaled on the first smooth portion 2 of the power shaft for longitudinal movement into and out of engagement with a member such as a flywheel gear 8 of an engine to be started. A screw shaft 9 is slidably but non-rotatably mounted on the splined portion 4 of the shaft and is provided with a counterbore 11 in which an abutment ring 12 is fixedly mounted in any suitable way as by welding or brazing. Ring 12 has a sliding fit on the reduced smooth portion 5 of the power shaft and abuts against the shoulders 6 on the power shaft to define the normal position of the screw shaft. A spring 13 bears at one end against the ring 12 and at its other end against a thimble 14 which partially encloses and retains a cross pin 15 located adjacent the end of the power shaft.

20 A barrel member 16 is rigidly fixed in any suitable manner as indicated at 17 to the pinion 7 in telescoping relation with the screw shaft 9 and is provided at its free end with a radial flange 18. A nut 19 is threaded on the screw shaft 9 with a comparatively low pitch and is movable therealong into engagement with an abutment in the form of a shoulder 21 which defines the operative position of the nut. Means for normally retaining the nut in idle position as illustrated, is provided in the form of an anti-drift spring 22 bearing against a flange 23 on the stop shoulder 21 of the screw shaft, and against a seat 24 on the nut 19.

25 A thrust connection is provided between the nut and pinion in the form of a thrust ring 25 located between the nut and the free end of the barrel 16. A yielding driving connection is provided between the nut 19 and the pinion barrel 16 comprising a sleeve 26 having a threaded connection with the exterior of the nut 19, which thread is of comparatively high pitch and of opposite hand to the screw shaft. An outer barrel member 27 is fixed to the sleeve 26 as by means of lugs 28 of the sleeve extending into slots 29 of the barrel, and retained therein by means of a split lock ring 31. The outer barrel 27 is provided with an inwardly extending flange 32, and a ring 33 of elastically deformable material is located between the pinion barrel and outer barrel and between the flange 18 of the pinion barrel and flange 32 of the outer barrel. As here shown, flange 18 is provided with lugs 34 extending into the slots 29 of the outer barrel so as to spline the pinion barrel to the outer barrel whereby the ring 33 of elastically deformable material is sub-

jected to compression only during the operation of the drive.

The threads of the screw shaft 9 terminate at a short distance from the end of the screw shaft, leaving a smooth portion 35 on which the double threaded nut 19 is normally located. Means for insuring engagement of the threads of the nut with the threads of the screw shaft upon actuation of the power shaft, is provided in the form of a re-entry spring 36 located between the screw shaft and pinion. Means for confining the nut within the sleeve 26 is provided in the form of a split lock ring 37 located in the end of the sleeve. A thimble 38 is preferably provided to protect the ring 33 from 15 scuffing by the telescoping action of the inner and outer barrels during the operation of the drive.

In operation, starting with the parts in the positions illustrated, actuation of the power shaft 2 causes rotation of screw shaft 9 whereby the nut 19 threads itself along the screw shaft into engagement with the abutment shoulder 21 thereon. This longitudinal motion of the nut is transmitted through the thrust ring 25 to the pinion barrel 16 which moves the pinion into operative position in abutting relation with the shoulder 3 on the power shaft. The pinion 7 engages the shoulder 3 just prior to the engagement of the nut with the abutment 21 on the screw shaft, whereby the screw shaft is caused to move backward, against the pressure of the spring 13 until the shoulder 21 engages the nut 19. The nut is thus effectively locked to the screw shaft whereby further rotation of the power shaft 2 causes the nut to rotate in the sleeve 26 whereby said sleeve is caused to move backward or to the right in Fig. 1 since it is threaded in the opposite direction to the threads of the screw shaft. The backward movement of the sleeve 26 is transmitted by the lock ring 31 to the outer barrel 27 which thereupon compresses the ring 33 between the flange 32 of the outer barrel and the flange 18 of the pinion barrel. When sufficient torque has been built up by the resistance to compression of the member 33, the pinion 7 will be caused to rotate with the power shaft and crank the engine. When the engine starts, the acceleration of the pinion 7 causes the parts to be returned to their idle positions as illustrated.

In case during the meshing operation a tooth of the pinion 7 should abut against a tooth of the engine gear 8 so as to obstruct the longitudinal movement of the pinion, the screw shaft 9 will be caused to move backward, compressing the mesh-enforcing spring 13 until sufficient torque has been built up in the threaded connection between the screw shaft and nut to cause the pinion to be indexed into proper meshing position. When this takes place, the spring 13 expands and snaps the pinion into initial mesh with the engine gear, whereupon meshing and driving take place as usual.

In Figs. 2 and 3 of the drawings, there is illustrated an embodiment of the invention substantially similar to that illustrated, but adapted to an outboard installation in which the pinion moves away from the starting motor rather than toward the starting motor during the meshing operation. As there illustrated, the power shaft 41 has a reduced portion 42 providing a shoulder 43, spline grooves 44 and a further reduced smooth portion 45 flush with the bottoms of the spline grooves. A bearing sleeve 46 is mounted

on the smooth portion 45 of the shaft and is retained on the shaft by a thrust collar 47 which bears against and partially encloses a cross pin 48 traversing the free end of the power shaft. 5 A pinion 49 is slidably journaled on the sleeve 46. A screw shaft 51 is slidably but non-rotatably mounted on the splined portion 44 of the power shaft and is normally held in abutting relation with the sleeve 46 by means of a spring 52 bearing at one end against a washer 53 seated against the shoulder 43 of the power shaft, and at its other end against a thimble 54 slidably mounted on the power shaft adjacent the end of the screw shaft 51. The remaining parts of this embodiment of the invention are the same as those in Fig. 1 and are similarly numbered so that further description thereof is deemed unnecessary.

In the embodiment of the invention illustrated in Figs. 4 and 5, the arrangement of the parts is substantially similar to that illustrated in Fig. 1 except that in this case the screw shaft 61 has its stop collar 62 welded or brazed thereon, and a bushing 63 is welded or brazed in the end of the screw shaft and is provided with slots 64 through which the cross pin 65 extends. The mesh-enforcing spring 66 bears in this instance directly on the end of the screw shaft. The flange 67 is here shown as welded or brazed to the pinion barrel 68, the end of which pinion barrel bears directly against the internally and externally threaded nut 69. In this case, the radial flange 67 of the pinion barrel is not splined to the outer barrel 71 whereby the ring of elastically deformable material 72 forms the sole driving connection between the pinion 73 and the outer threaded sleeve 74 so that the ring 72 is subjected to both compression and torsion. The remaining parts of this drive and the operation thereof are the same as previously described with the exceptions noted.

In Fig. 6 of the drawings there is illustrated a power shaft 81 having a splined portion 82 and a reduced smooth portion 83 flush with the bottoms of the splines. A pinion 84 is slidably journaled on the shaft 81 for longitudinal movement into and out of engagement with an engine gear 85. A screw shaft 86 is non-rotatably mounted on the splined portion 82 of the power shaft and is prevented from longitudinal movement by means of a cylindrical member 87 fixed in a counterbore of the screw shaft as by welding or brazing and rigidly connected to the power shaft by means of a cross pin 88 retained by a lock ring 89.

An internally and externally threaded nut 91 is mounted on the screw shaft, the internal thread being of comparatively low pitch and the external thread of high pitch and opposite hand. A sleeve member 92 is threaded on the nut 91 and is rigidly connected to an outer barrel member 93 as by means of radial lugs 94 extending into slots 95 of the outer barrel. A ring 102 of elastically deformable material is mounted between the inner and outer barrels and between the flange 99 of the pinion barrel and an inwardly extending flange 103 of the outer barrel. A thrust plate member 104 is splined in the outer barrel 93 as by means of radial lugs 105 slidably mounted in the slots 95 of the barrel, and a yielding thrust connection from the plate 104 to the pinion barrel 97 is provided in the form of a ring 106 of elastically deformable material interposed between the plate 104 and the flange 99 of the pinion barrel. Plate 104 is pro-

vided with a central opening 107 loosely surrounding the screw shaft 86 whereby the nut 91 is adapted to engage the plate and move it longitudinally, which motion is transmitted through the elastic thrust ring 106 to the pinion barrel and pinion. Longitudinal motion of the plate 104 is limited by a shoulder 108 on the screw shaft 86 which thereby defines the operative position of the pinion 84. An anti-drift spring 109 is provided for normally maintaining the parts in idle position, a re-entry spring 111 insures engagement of the threads of the nut with those of the screw shaft, and a split ring 112 retains the nut in the sleeve 92.

In the operation of this embodiment of the invention, rotation of the power shaft 81 is transmitted through the splines 82 to the screw shaft 86 whereby the nut 91 threads itself along the screw shaft, moving the pinion 84 into engagement with the engine gear 85. When the thrust plate 104 engages the shoulder 108 on the screw shaft, further movement of the nut is prevented, whereupon the sleeve 92 is caused to move backward, drawing the outer barrel 93 with it and thereby compressing the elastic ring 102 until sufficient torque is built up to cause rotation of the engine member. If, during the meshing operation, tooth abutment should occur between the pinion and engine gear so as to stop the longitudinal movement of the pinion, the elastic ring 106 is adapted to compress to allow time for friction to build up in the threads of the screw shaft and nut to cause indexing of the pinion, whereupon the ring 106 expands to secure initial mesh of the pinion, after which meshing and driving take place in the usual manner.

In this embodiment of the invention, the length of the nut 91, the slots 95 in the outer barrel and the dimensions of the elastic ring 102 are such that if the drive is subjected to a predetermined overload, the sleeve 92 may screw off the end of the nut 91, thus permitting the nut to overrun. The maximum torque transmitted by the drive is thereby limited to a predetermined value.

In the embodiment of the invention illustrated in Figs. 7 to 11, a power shaft 115 is provided with a spline portion 116 and a smooth reduced portion 117. A pinion 118 is slidably journaled on the power shaft in position to engage and drive an engine gear 119. A screw shaft 121 is non-rotatably mounted on the splined portion 116 of the power shaft and is prevented from longitudinal movement by a cylindrical member 122 mounted in a counterbore of the screw shaft and fixed to the power shaft by a cross pin 123. Pin 123 is retained by a ring 124 which is locked on the cylindrical member 122 by a split ring 125.

An internally and externally threaded nut 126 is threaded on the screw shaft with a low pitch thread, and a sleeve 127 is threaded on the nut with a high pitch thread of opposite hand. An outer barrel member 128 is fixed to the sleeve 127 as by means of lugs 129 of the sleeve extending into slots 131 of the barrel member and retained by a split lock ring 132. An inner barrel member 133 is fixed to the pinion 118 and has a radial flange 134 provided with lugs 135 slidably mounted in slots 131 of the outer barrel so as to spline the pinion barrel to the outer barrel. A ring 136 of elastically deformable material is mounted between the pinion barrel and outer barrel and between the flange 134 of the pinion barrel and a terminal flange 137 on the outer barrel. A yielding thrust connection between

the nut 126 and the pinion barrel 133 is provided in the form of a thrust plate 138 and a yielding ring of elastically deformable material 139 interposed therebetween. Screw shaft 121 is provided with a stop shoulder 141 adapted to be engaged by the nut 126 to define its operative position and thereby define the meshing position of the pinion 118.

An anti-drift spring 142 is provided for normally retaining the parts in idle position, and a re-entry spring 143 between the screw shaft and pinion insures engagement of the nut 126 with the threads of the screw shaft upon rotation of the power shaft.

15 In the operation of this embodiment of the invention, rotation of the power shaft 115 and screw shaft 121 causes the nut 126 to be traversed to the left in Fig. 7 until it engages the shoulder 141 on the screw shaft as illustrated in Fig. 9. 20 Further rotation of the power shaft causes the sleeve 127 to be threaded back on the nut, thus compressing the ring 136 of elastically deformable material between the flange 134 of the pinion barrel and flange 137 of the outer barrel until sufficient torque has been built up to crank the engine. In case of tooth abutment between the pinion and engine gear, the yielding thrust member 139 compresses to provide time for friction to build up in the threaded connection to index the pinion into proper position, whereupon the ring expands to secure initial mesh and the cranking operation is resumed. In case of 25 overload, the sleeve 127 may move backward sufficiently to run off the threads of the nut 126 so as to permit the nut to rotate, thereby limiting the maximum torque transmitted by the drive.

30 Although certain embodiments of the invention have been shown and described in detail, it will be understood that other embodiments are possible and various changes may be made in the design and arrangement of the parts without departing from the spirit of the invention as defined in the claims appended hereto.

35 45 What is claimed is:

1. In an engine starter drive, a power shaft, a screw shaft mounted thereon for rotation therewith, an internally and externally threaded nut on the screw shaft, a pinion slidably journaled on the power shaft, a sleeve threaded on the nut, means transmitting longitudinal movement of the nut to the pinion in a direction to mesh the pinion with a member of an engine to be started, and means including a yielding member resisting longitudinal movement of the sleeve away from the pinion and transmitting rotation of the sleeve to the pinion.

on the power shaft, means including a barrel fixed to the pinion transmitting longitudinal movement of the nut to the pinion, said screw shaft having an abutment limiting longitudinal movement of the nut thereon in a direction to mesh the pinion with a member of an engine to be started, a sleeve threaded on the nut, and means including an elastically compressible member resisting longitudinal movement of the sleeve away from the pinion barrel and transmitting rotation of the sleeve to the pinion barrel.

4. In an engine starter drive, a power shaft, a screw shaft mounted thereon for rotation therewith, a pinion slidably journalled on the power shaft, a barrel fixed to the pinion having a radially extending flange, an internally and externally threaded nut on the screw shaft, means transmitting longitudinal movement of the nut to the barrel in a direction to mesh the pinion with a member of an engine to be started, an outer barrel surrounding the pinion barrel having an inwardly extending flange, a ring of elastically deformable material surrounding the pinion barrel within the outer barrel between said flanges, and a sleeve non-rotatably connected to the outer barrel threaded on said nut.

5. In an engine starter drive, a power shaft, a screw shaft mounted thereon for rotation therewith, a pinion slidably journalled on the power shaft, a barrel fixed to the pinion having a radially extending flange, an internally and externally threaded nut on the screw shaft, said threads being of opposite hand, an outer barrel surrounding the pinion barrel, a ring of elastically deformable material between said barrels, means transmitting longitudinal movement of the nut to the pinion barrel, a sleeve threaded on the nut, and means transmitting longitudinal movement of the sleeve to the outer barrel.

6. In an engine starter drive, a power shaft, a screw shaft non-rotatably mounted thereon, a pinion slidably journalled on the power shaft for movement into and out of engagement with a member of an engine to be started, a nut threaded on the screw shaft, said screw shaft having an abutment defining the operative position of the nut, a barrel fixed to the pinion telescoped over the screw shaft and connected for longitudinal movement with the nut, a ring of elastically deformable material surrounding the pinion barrel, an outer barrel surrounding said ring, and means for yieldingly transmitting rotation from the nut to the pinion barrel including a sleeve threaded on the nut and rigidly connected to the outer barrel.

7. An engine starter drive as set forth in claim 6 in which the length of the threads on the nut and sleeve, and the compressibility of the ring of elastically deformable material are such that the sleeve may run off the threads of the nut and permit the nut to overrun in case of an overload on the drive.

8. In an engine starter drive, a power shaft, a shaft splined thereon having an external thread of comparatively low pitch, an abutment defining the operative position of the screw shaft, means yieldingly holding the screw shaft against said abutment, a pinion slidably journalled on the power shaft, a barrel fixed to the pinion, an internally and externally threaded nut on the screw shaft, means transmitting longitudinal movement of the nut to the pinion, a sleeve threaded on the nut with a comparatively high pitch of opposite hand to the screw shaft, and yielding means resisting longitudinal movement of the sleeve and

transmitting torque therefrom to the pinion barrel.

9. In an engine starter drive, a power shaft, a screw shaft splined thereon having an external thread of comparatively low pitch, an abutment defining the normal position of the screw shaft, means yieldingly holding the screw shaft against said abutment, a pinion slidably journalled on the power shaft, a barrel fixed to the pinion having an outwardly extending flange, an internally and externally threaded nut on the screw shaft, means for transmitting longitudinal movement of the nut to the pinion, a sleeve threaded on the nut with a comparatively high pitch of opposite hand to the screw shaft, an outer barrel member fixed to the sleeve having an inwardly extending flange, and a ring of elastically deformable material between the barrel members adapted to be compressed between said flanges to form a yielding driving connection for the pinion.

10. In an engine starter drive, a power shaft, a screw shaft fixed thereon, a pinion slidably journalled on the power shaft having a barrel fixed thereto, a nut threaded on the screw shaft, a yielding thrust connection between the nut and the barrel including a thrust ring of elastically deformable material, a sleeve having a threaded connection with the nut of opposite hand to the screw shaft, and a yielding driving connection between the sleeve and pinion barrel including a ring of elastically deformable material compressed by longitudinal movement of the sleeve.

11. In an engine starter drive, a power shaft, a screw shaft fixed thereon, a pinion slidably journalled on the power shaft having a barrel fixed thereto, a nut threaded on the screw shaft, a yielding thrust connection between the nut and the barrel including a thrust ring of elastically deformable material, a sleeve having a threaded connection with the nut of opposite hand to the screw shaft, and a yielding driving connection between the sleeve and pinion barrel including an outer barrel member fixed to the sleeve and a ring of elastically deformable material compressed between the inner and outer barrels by longitudinal movement of the sleeve.

12. In an engine starter drive, a power shaft, a screw shaft fixed thereon, a pinion slidably journalled on the power shaft having a barrel fixed thereto, a nut threaded on the screw shaft, a yielding thrust connection between the nut and the barrel including a thrust ring of elastically deformable material, a sleeve having a threaded connection with the nut of opposite hand to the screw shaft, and a yielding driving connection between the sleeve and pinion barrel including an outer barrel member fixed to the sleeve and having a splined connection with the pinion barrel, and a ring of elastically deformable material compressed between the two barrels by longitudinal movement of the sleeve, said parts being so dimensioned as to permit the sleeve to run off the threads of the nut when the drive is subjected to a predetermined overload.

13. In an engine starter drive, a power shaft having a smooth portion, spline grooves adjacent thereto and a reduced smooth portion beyond the splined portion; a pinion slidably journalled on the first smooth portion, a screw shaft engaging the splined portion, and a collar fixed in the screw shaft bearing on said reduced smooth portion, the abutment of the collar against the end of the splined portion of the power shaft defining the operative position of the screw shaft thereon, a nut having a low pitch threaded connection with

the screw shaft, said screw shaft having an abutment defining the operative position of the nut, a sleeve having a high pitch connection to the nut of opposite hand, a thrust connection between the nut and pinion, and a yieldable driving connection between the sleeve and pinion.

14. An engine starter drive as set forth in claim 13 in which the thrust connection between the nut and pinion comprises a ring of elastically deformable material adapted to yield when longitudinal movement of the pinion is obstructed. 10

15. An engine starter drive as set forth in claim 13 in which the pinion has a splined connection to the sleeve, and the yielding driving

connection includes a ring of elastically deformable material and means for compressing said ring to resist relative longitudinal movement of the sleeve and pinion.

16. An engine starter drive comprising a pinion, an internally and externally threaded nut, yielding means cooperating with the internal threads of the nut for traversing the pinion into and out of engagement with a member of an engine to be started, and means cooperating with the external threads of the nut forming a yielding driving connection for the pinion, substantially as shown and described.

THOMAS B. MARTIN.
